B. D. MILLER

ICE CREAM DISPENSER

Filed Dec. 5, 1921

Inventor

Benj. D. Miller,
By Hiram B. Swartz, Atty.

UNITED STATES PATENT OFFICE.

BENJAMIN D. MILLER, OF WOOSTER, OHIO.

ICE-CREAM DISPENSER.

Application filed December 5, 1921. Serial No. 520,148.

To all whom it may concern:

Be it known that I, BENJAMIN D. MILLER, a citizen of the United States, residing at Wooster, in the county of Wayne and State of Ohio, have invented a new and useful 5 Ice-Cream Dispenser, of which the following is a specification.

My invention relates to devices for dispensing ice cream from large receptacles to small ones, and its principal object is to provide a simple and efficient means for dipping ice cream from receptacles wherein it is stored, and dispensing the same in small and measured quantities to customers, 15 and to make the dispensing thereof more sanitary and easier than heretofore.

It consists of the novel device and mechanism hereinafter fully set forth and stated in the appended claim.

20 My invention is illustrated by the accompanying drawings in which similar letters and figures of reference indicate like parts.

Referring to the drawings, Fig. 1 is an exterior side view of a device embodying 25 my invention; Fig. 2 is a vertical and longitudinal section of Fig. 1 on the dotted line 2—2; Fig. 3 is a detail view of an auxiliary means for swiping off the cream from the dispensing cup, detached therefrom; and 30 Fig. 4 is a lateral cross section of Fig. 1 on the dotted line 3—3.

In the drawings, A and B are hollow tubes having telescopic relation to each other, the member A being closely fitted to 35 slide reciprocally within the tube B. C is a terminal cup integral with the lower end of the tube B, and open at its lower end C'. E is a head or dispensing end of my device, comprising a flanged rim attached to the

40 lower end of the tube A, and having a central opening into the tube for the upward escape of air therethru, and fitted to reciprocate within the terminal cup C for the purpose of expelling ice cream therefrom, 45 as hereafter stated. F is a thumb latch, operable outwardly thru a slot G in the tube A by means of a spring f located within the tube, and adapted to engage a notch in the band b at the top of the tube B, when the

50 tube A is drawn out to its limits. The latch has a two fold object—first, to hold the tube members A and B in extended relation while the cup end C' is manually pushed endwise into the mass of ice cream within the ice cream receptacle wherein it is stored, and 55 the flanged head E, as a piston head, is held

thereby from reciprocating within the cup; and, secondly, to impel the tube B to rotate with the rotation of the tube A, after the cup member has been pushed into the mass 60 of ice cream within the receptacle thereof, which rotary movement is essential to separating the cream within the cup from that within the receptacle, as hereafter stated.

The thumb-latch F fits snugly into the 65 slots G and G', respectively, as an air tight stopper, and its lower edge extends outwardly and is fitted to engage any one of the several notches in the band b which surrounds the upper end of the tube B, for 70 convenience in handling the device.

Said band and tube are also fitted to lie closely upon the tubular member A, so as to practically prevent the passage of air 75 between them, when operating in ice cream.

I am aware that air valves, for a similar purpose, have been heretofore provided, located in the top of the dispensing cup, and such I do not broadly claim. Such arrangement is defective on account of their 80 nearness to the ice cream, which is liable to stop them up, and escape therethru. I overcome these defects by locating the valve H at the top of the tube A, and making a continuous air duct therein opening directly thru the plunger head E into the dispensing cup C.

D is a ring of metal, which is mounted to reciprocate loosely over the outer surface of the cup C, and is provided with a series 90 of rods d d, secured thereto, and adapted to lie snugly against the said outer surface of said cup, and in line therewith. By the rotation of said metal rim D the rods swipe off the ice cream that may lodge thereon, 95 and downward movement of the rim over said surface also aids in accomplishing a like object.

But this feature is only of occasional use, and is not absolutely essential to its use generally.

The air valve H, fitted to the top of the tube A, creates a suction therein when the dispensing cup C is being withdrawn from the mass of ice cream within the ice cream 105 receptacle of storage. This valve acts automatically, and effectually closes the upper end of the tube A, whereby the ice-cream within the cup is held therein. However, this valve is unnecessary where the ice cream is sufficiently frozen to prevent running, as in such case the friction within the 110

cup, whose walls are parallel, is sufficient to retain the ice cream therein until forced out by the action of the piston head E.

Measurement of the ice cream is determined by the size of the dispensing cup C, which may be made of any size or shape desired to suit the trade, the normal standard being one quart. To adapt the device to lesser measures, I provide a secondary slot G' in the body of the tube B, fitted to engage the thumb latch F at F², (Fig. 1), thereby holding the piston head at the intermediate position within the cup at E², while the cup is pushed into the mass of ice cream, the handle on the end of tube A being, in such case moved down in the direction of the arrow m to the intermediate position a². Other predetermined measurements may be made in like manner.

The operation of my device is as follows— The tubular members A and B being drawn apart to their limits, the thumb latch F engages one of the notches e, whereby said members are held in extended relation, and rotary movement of one upon the other is prevented. The dispensing cup member C is then pushed into the mass of ice cream in the ordinary storage receptacle until it fills the cup; thereupon, by giving the handle a slight twist in either direction, the cream within the cup is broken off from the mass within the receptacle, and the device is then drawn out, the ice cream within the cup being held therein by friction of the side walls, aided, in case the cream is not solidly frozen, by the suction within the tubes created by the air valve H. To discharge the ice cream from the dispensing cup C, the tubular member B is grasped by the other hand of the operator immediately opposite the thumb latch F, which, being pressed down, permits the member A to telescope within the tubular member B, thereby pushing out the ice cream from the cup by action of the piston head E to its limits at E' at the bottom C' of the dispensing cup.

This pressure may also be utilized to compress the dispensed cream within ordinary ice cream cartons, and, for the purpose, the dispensing cup may be either cylindrical or angular, the piston head being shaped to conform thereto, and the dispensed mass may be shaped either in brick form or otherwise, as may be desired.

I am also aware that a plunger rod, engaging a plunger head, has heretofore been constructed to reciprocate thru a stem, and movement therein limited by means of a manually operable pin-stop passing thru said rod, and such I do not claim broadly. In such case the means for actuating the pin-stop are necessarily outside of the apparatus, exposed to view, and difficult to handle, and too expensive for general use. In my device a latch is driven outwardly from within the tubular stem, and is adapted thereby to engage any one of a series of notches in the top of the outer tubular member, and also to act as a stopper of air, as aforesaid; and the latch is readily disengaged from the notches, respectively, simply by pressure of the thumb thereon, and returns to its normal position, by action of the spring bar within the tube, automatically, as aforesaid.

The various movements of the parts are indicated by the dotted outlines a', F', and a², F², and the arrows m, n, and o, p.

Having thus fully described my invention, what I claim is—

In a device of the character described, the combination with a tubular body; a dispensing cup on one end of said body, opening outwardly; a rim surrounding the other end of said body, having a series of notches therein; a tubular shaft longer than said body, and fitted to reciprocate closely within said rim; a disk on the lower end of said tubular shaft, having a central opening and fitted to reciprocate within said dispensing cup; an air valve closing the top of said tubular shaft; a handle at the upper end of said shaft; a longitudinal slot in said shaft opposite said rim notches when drawn out to its limits, and a spring actuated bar mounted within said tubular shaft carrying a thumb latch, said latch fitted to register closely with said longitudinal slot, and adapted to engage any one of said notches, automatically, substantially as set forth and for the purpose specified.

In witness whereof, I hereunto set my hand this 24 day of September, 1921.

BEN D. MILLER.

In presence of two witnesses:

HIRAM SWARTZ,
WALTER J. MONGEY.
